UNITED STATES PATENT OFFICE.

LEWIS C. MYERS, OF BROOKLYN, NEW YORK, ASSIGNOR TO ROYAL TYPEWRITER COMPANY, INC., OF NEW YORK, N. Y., A CORPORATION OF NEW YORK.

TYPE-WRITING MACHINE.

1,324,167.

Specification of Letters Patent.

Patented Dec. 9, 1919.

Application filed March 26, 1918. Serial No. 224,716.

To all whom it may concern:

Be it known that I, LEWIS C. MYERS, a citizen of the United States, and a resident of the borough of Brooklyn, in the city of New York, county of Kings, and State of New York, have invented certain new and useful Improvements in Type-Writing Machines, of which the following is a specification.

- 10 The present invention relates generally to typewriting machines and has more particularly reference to the margin controlling devices thereof together with means for effecting bell ringing and line locking.
- 15 In Patent No. 1,267,769 dated May 28, 1918 there is disclosed a typewriting machine of the visible type in which there are visible margin controlling means located in rear of the type bars and adjacent the front
- 20 of the carriage and platen, said means consisting, in part, of two margin rails, one on each side of the printing center, thus affording between them passage for the type bars to the printing point. In that case, the left hand margin rail is rigid while the right hand margin rail is pivotally mounted on horizontal supports so as to constitute, in effect, a rocking member by means of which bell ringing and line locking may be
- 25 effected.

30 The main object of this invention is to obviate the necessity of having a rocking margin rail on the right hand side of the printing center and to this end consists, as one feature of the invention, in means associated with a rigid right hand margin rail whereby the traverse of the platen will actuate instrumentalities, in any adjusted position of the margin stop, to effect bell ringing and line locking in the proper manner.

40 Other features of the invention will appear as the specification proceeds.

45 In the accompanying drawings, the invention is clothed in a concrete and preferred form. However, variations may be made without departing from the invention.

In said drawings:

50 Figure 1 is a top plan view of a typewriting machine of the character shown in the patent granted to Edward B. Hess, No. 1,267,769, and here shown largely in diagrammatic outline with elements omitted

for the purpose of more clearly illustrating the invention:

55 Fig. 2 is a vertical sectional view through the machine, showing the relative arrangement of the parts embodying my invention when the machine is viewed in cross section, unnecessary elements being omitted;

60 Fig. 3 is a view substantially similar to Fig. 2 but on a larger scale to more clearly indicate the construction embodying the invention:

65 Fig. 4 is a detail plan view, partly in section and partly in elevation, of the right hand margin controlling device as shown in Fig. 1.

70 Fig. 5 is a sectional view on the line 5—5 of Fig. 4; and

Fig. 6 is a detail sectional view on the line 6—6 of Fig. 5.

75 1 indicates a frame work of any suitable construction, such as that generally employed in the well known Royal typewriting machine; and 2 is the dust shed or top plate, which covers, in a general way, the mechanism contained within the machine. 3 indicates suitable key levers such as are commonly employed; and 4 the type bars, only one of which is shown to represent, in a manner well understood, a series. 5 is a platen of suitable construction mounted, in any convenient manner, in a carriage 6 having a race way 7 and having suitable 85 means, represented here by the member 8, for effecting case shifting. The shift mechanism employed is that of the well known Royal typewriter such as is described in Patent No. 1,227,438. 9 is a bell or gong, shown as being supported directly beneath dust shed 2 by means of a screw 10 which, in this instance, also serves to fasten a ribbon housing 11 in position. 12 is a line locking blade, carried by lever 13, 90 extending transversely of the machine and normally held out of line locking position by means of a spring 14, in a manner well understood, and which, when brought under locking surfaces 15 of the key levers, serves 95 to line lock the entire series of keys.

16 is the left hand margin rail and 17 the right hand margin rail; 18, the left hand margin stop and 19, the right hand margin stop, while 20 and 21 represent stop blocks 100 carried by the platen or carriage and having

engagement with the margin stops in a manner to be hereinafter described. It will be seen, especially from Fig. 1, that the margin rails are located one on each side of the printing center, generally designated by 22; and that the dust sheds are so arranged as to afford free passage of the type bars 4 to and from said printing center. It will be understood from consideration of Fig. 2, that, 5 margin rails 16 and 17 are located immediately in front of the platen and on either side of the printing center thereof and below a horizontal line and in front of a vertical line drawn through the axis of the 10 platen. In fact, as here shown, said margin rails are below a horizontal line tangent to the underside, and in front of a vertical line tangent to the front side, of the platen. The two margin rails 16 and 17 are mounted in 15 any suitable manner upon the frame-work of the machine, a convenient method being here represented by screw 23 which latter also serves to hold the rack 24 in position. This rack may be considered as part of the 20 margin rail. To cause stop blocks 20 and 21 to properly coöperate with the margin stop they are, in the present instance, pivotally supported on horizontal pivots 25 and a spring 26 is utilized for normally urging the 25 lower end 27 of said stop blocks into lowermost position in the path of the margin stops on the rails. During normal traverse of the carriage, stop blocks 20 and 21 will be carried beyond the carriage frame and since 30 they will consequently then occupy the lowermost possible position, they will project below the top surface of the dust sheds. For this reason, inclined surfaces located on top of the dust sheds, such as 70, are employed over which during the traverse of the 35 carriage the stop blocks ride and thereby bring the lower surface 27 of said stop block into a position that is in the path and plane of the margin stops. There is a further advantage in this construction of stop 40 block in that, it will be observed from Fig. 2, if the carriage and platen are moved into their shifted position, as indicated in dotted lines, the pull of spring 26 will maintain 45 stop block 20, or 21, in proper relation to its margin stop. It will also be understood that by manipulation of handle 28 in opposition to the action of spring 26, the stop blocks 50 may be moved upwardly out of the path of the margin stops to admit of additional writing at either end.

The right hand margin stop 19 is provided with a locking member 33 having teeth 34 at its inner end which serve to engage with corresponding teeth in rack 24 and which is actuated by means of a pin 35 engaged in an aperture 36 and extending upwardly through an elongated slot 37 in margin stop 19. Normally, the locking 55 member 33 is urged into its locked position

by means of spring 38 but the action of this spring is overcome, at will, by the operator by means of handle 39 pivoted at 40 and engaging the member 35 to move it out of engagement with the teeth in rack 24. By 70 these means, the right hand margin stop can be moved into any adjusted position. Suitably mounted on the right hand margin stop 19 is a latch or locking member 41 supported on a vertically extending pivot 42 and 75 provided with two engaging portions 43 and 44 and also with a downwardly extending projection 45 that passes through an opening in the dust shed and terminates in fork 46. Extending beneath dust shed 2 is an actuating member here taking the form of a rock shaft 48 that extends horizontally and is suitably supported in the dependent lugs 49 that project from the underside of the frame-work. Mounted upon this rock shaft 80 is a bail 50 with which the forked member 46 engages. It will now be understood that if margin stop 19 is adjusted to any position within the limits of its construction, forked member 46 will slide on bail 50 and will provide operative engagement between the margin controlling device and rock shaft 48. Loosely mounted on said rock shaft 48 is a bell hammer 51, here shown in the form of a wire bent around said rock shaft and having a doubled-back portion 52 that serves as a stop and engages with the underside of the dust shed. The bell hammer is normally held in its uppermost position by means of spring 53. Mounted fast on rock shaft 48 is 100 a bell crank 54, one end 55 of which has a portion 56 bent over the bell hammer so as to lower and depress it when the rock shaft 48 is rocked in one direction. The other arm 57 of said bell crank is connected by 105 means of link 58 to a vertically extending rock shaft 59 mounted in suitable bearings 60 in the rear of the machine and having a suitable connection, such as 61, by means of which it is connected to line lock shaft 13. 110 It will now be understood that, when the carriage is moved in a left hand direction, stop block 21 will first encounter the engaging portion 43, thereby turning the member 41 on its pivot 42 and causing the forked extension 46 to turn bail 50 toward the left in Fig. 2 thereby causing rock shaft 48 to turn and carry with it bell hammer 51; and, if stop block 21 passes beyond the point where it engages portion 43 of member 41, gravity 115 will restore rock shaft 48 to its central position and thereby permit spring 53 to sound the gong or bell 9 thereby indicating to the operator that the end of the line is being approached. As the carriage continues its 120 traverse in the left hand direction, stop block 21 will next encounter engaging portion 44 and thereby swing the member 41 on its pivot 42 until said member 44 comes in abutting engagement with locking member 130

33. This will cause forked extension 46 to move the bail in a direction opposite to that for bell ringing (to the right from position in Fig. 2) and will effect rocking of rock shaft 48 thereby causing a pull to be exerted through link 58 to the vertically extending rock shaft 59 which, in turn, transmits the motion and brings the line lock blade 12 under the surface of the key levers, thereby locking the machine. Should it now be desired to write additional matter, handle 28 is depressed thereby lifting the end 27 of stop block 21 and thus causing spring 14 of the line lock mechanism to restore the parts 15 to normal position and out of line locking position. Spring 14 also tends to move rock shaft 48 into its central position, the movement of rock shaft 48 also being facilitated by the action of gravity.

20 The member 33 is also provided with a taper surface, as indicated in the drawings, (Fig. 6) so that as stop block 21 is elevated to admit of additional writing, it will ride down said incline gradually and without 25 shock to the parts; and; when drawing the carriage in a right hand direction, said stop block 21 will ride up said incline and admit of uninterrupted traverse of the platen in a right hand direction.

30 The left hand margin stop is of substantially the same construction as the margin stop 19 except that it is not provided with a rocking member 41. In all other essentials, however, it is the same in that it is provided 35 with a locking member 33 that is manipulated by means of a handle 39, in the manner described in connection with the right hand margin stop. It will be understood (when actuating the usual carriage release mechanism) that during the right hand traverse of the carriage the stop block 20 will come in engagement with the member 33 of margin stop 18, thereby preventing further advance of the carriage. Should it be desired to 40 print beyond the point provided for by the adjustment of the margin stop, stop block 20 will be manipulated in a manner similar to stop block 21 carrying it over abutment member 33. When the carriage then begins 45 its left hand traverse, stop block 20 will ride up the inclined surface of member 33 and continue uninterruptedly in the left hand direction.

I claim—

55 1. Bell ringing and line locking mechanism comprising: a platen having a stop block, a pivotally supported actuating member rocked in opposite directions from a central position under the influence of the 60 stop block of the platen during the traverse of the latter, a bell ringing device, a line locking mechanism, means for operating the bell ringing device from the actuating member when the latter is rocked in one direction from its central position, and means

for operating the line locking mechanism from the actuating member when the latter is rocked in the other direction from its central position.

2. In a typewriting machine: a margin 70 rail, a margin stop adjustable on said rail, a rocking lever carried by said margin stop, a platen, a stop block for actuating said rocking lever twice during traverse of the platen, a bell ringing device, a line locking 75 mechanism, and means for actuating said device and mechanism from said rocking lever.

3. In a typewriting machine: a margin 80 rail, a margin stop adjustable on said rail, a rocking lever carried by said margin stop, a platen, a stop block for actuating said rocking lever twice during traverse of the platen, a bell ringing device, a line locking mechanism, means for actuating said device and mechanism from said rocking lever, and a pivotal mounting for said stop block on the platen admitting of its removal out of the path of said rocking lever to admit of additional writing. 85

4. Bell ringing and line lock mechanism comprising: a platen having a stop block, a margin rail adjacent the platen, a margin stop adjustable on said rail, and an actuating member supported independently of the 95 margin stop and operable therefrom in any adjusted position of the latter, a bell ringing device, a line locking mechanism, and means for operating said device and mechanism from said actuating member. 100

5. In a typewriting machine: a platen having a stop block, a margin rail adjacent the platen, a margin stop adjustable on said rail, a rocking member carried by said margin stop and movable in opposite directions 105 from a central position by the stop block during normal traverse of the platen, and an actuating member supported independently of the margin stop and operable from the rocking member in any adjusted position of the margin stop. 110

6. In a typewriting machine: a margin rail, a movable member extending lengthwise beneath said rail, and a margin stop for actuating said movable member slidably 115 mounted on the margin rail and slidably and operatively connected with the movable member in any adjusted position.

7. In a typewriting machine: a rigidly mounted margin rail, a movable member extending lengthwise beneath said rail, a margin stop slidably mounted on the margin rail, and a latch pivotally supported on the margin stop and slidably and operatively 120 engaging with the movable member in any adjusted position of the margin stop. 125

8. In a typewriting machine: a margin rail, a rocking member extending lengthwise beneath said rail, a margin stop slidably mounted on the margin rail, and a latch 130

- pivotally supported on the margin stop and having a forked extension slidably engaging the rocking member in any adjusted position of the margin stop.
5. 9. In a typewriting machine: a margin rail, a rocking member extending lengthwise beneath said rail, a margin stop slidably mounted on the margin rail, a latch pivotally supported on the margin stop and 10 having a forked extension slidably engaging the rocking member in any adjusted position of the margin stop, a bell crank carried by said rocking member, a bell ringing device, a line locking mechanism, means for 15 operating the bell ringing device from one arm of said bell crank and for operating the line locking mechanism from the other arm of said bell crank.
10. In a typewriting machine: a rocking 20 bail mounted on the framing, a margin rail above said rocking bail, and a margin stop slidably mounted on the margin rail and slidably and operatively connected with the rocking bail.
- 25 11. In a typewriting machine: a dust shed, a rocking member pivotally supported beneath said dust shed, a margin rail mounted on top of said dust shed, a margin stop slidably mounted on said margin rail, and 30 means extending through said dust shed operatively connecting the rocking member and margin stop in any adjusted position of the latter.
12. In a typewriting machine: a dust shed, 35 a rocking member pivotally supported beneath said dust shed, a margin rail mounted on top of said dust shed, a margin stop slidably mounted on said margin rail, a member pivotally supported by said margin stop and 40 having a downwardly projecting forked extension extending through the dust shed and operatively engaging the rocking member in any adjusted position of the margin stop.
13. In a typewriting machine: a platen, a 45 stop block movable therewith, a margin rail, a margin stop adjustable on said rail, a latch pivotally supported on said margin stop and having two engaging portions successively 50 acted upon during the traverse of the platen by said stop block to turn the latch first in one, and then in the other direction about its pivotal center, and means actuated by said latch.
14. In a typewriting machine: a platen, a 55 stop block carried thereby, a margin rail, a margin stop slidably mounted on said margin rail, locking means for said margin stop, and a pivotally supported member on said 60 margin stop mounted to project into the path of the stop block and to be moved thereby into abutting engagement with the locking means.
15. In a typewriting machine: a platen, a stop block carried thereby, a margin rail, a 65 margin stop slidably mounted on said mar-
- gin rail, locking means for said margin stop, a pivotally supported member on said margin stop mounted to project into the path of the stop block and to be moved thereby into abutting engagement with the locking means, and means for effecting line locking from said pivotally supporting member. 70
16. In a typewriting machine: a platen, a stop block carried thereby, a margin rail, a 75 margin stop slidably mounted on the margin rail, a slidably mounted locking member on said margin stop to lock the latter in any adjusted position to the margin rail, said locking member also having an abutment portion, a pivotally supported member on the margin stop in the path of the stop block and adapted to be moved thereby into engagement with the abutment portion of the locking member during traverse of the 80 platen.
17. In a typewriting machine: a margin rail, a margin stop adjustable thereon, a 85 rocking member supported on a vertical pivot carried by said margin stop, a downwardly extending portion carried by said rocking member, and a second rocking member below the margin rail supported to turn on a horizontal pivot and to be actuated by the downwardly extending portion of the 90 rocking member on the margin rail.
18. In a typewriting machine: an actuating member comprising, a horizontally extending rock shaft, a horizontally extending rod carried by said rock shaft, and 100 means including a margin controlling device for engaging with the horizontally extending rod to actuate the rock shaft.
19. In a typewriting machine: a horizontally disposed rock shaft, a bail mounted on 105 said rock shaft, a margin stop, means for actuating said rock shaft from said margin stop through said bail, and a bell crank mounted on said rock shaft.
20. In a typewriting machine: a horizontally disposed rock shaft, a bail mounted on 110 said rock shaft, a rigid margin rail above said horizontal rock shaft, a margin stop mounted on said rail, means actuating said rock shaft from said margin stop through 115 said bail, and a bell crank mounted on said rock shaft.
21. In a typewriting machine: a horizontally disposed rock shaft, a rigid margin rail above 115 said horizontal rock shaft, a margin stop mounted on said rail, means for actuating the rock shaft from the margin stop, a vertically disposed rock shaft, line lock mechanism, means connecting the line lock mechanism and the vertically disposed 120 rock shaft, and means connecting the horizontally and the vertically disposed rock shafts.
22. A typewriting machine comprising: 125 printing elements comprising a transversely 130

- movable platen and forwardly recumbent type bars having a common printing center, two rigid margin rails, one on each side of said common printing center to afford there- 25
5 between passage of the type bars to the printing center, stop elements carried by the platen, one on each end thereof, a stop element on the right hand margin rail for limiting the left hand movement of the 10 platen and for admitting of its uninterrupted right hand movement, and a stop element on the left hand margin rail for limiting the right hand movement of the platen and permitting of its uninterrupted 15 left hand movement.
23. In a typewriting machine: a trans- versely movable platen, a stop block mov- able with the platen, a rigidly mounted margin rail located in front of the platen on 20 the right hand side of the machine, adjust- able means on said margin rail actuated by
- said stop block on the platen, and bell ring- ing mechanism and a line lock mechanism both actuated from the adjustable means on the margin rail. 30
24. In a typewriting machine: a trans- versely movable platen, a stop block mov- able with the platen, a margin rail adjacent the platen, a margin stop adjustable on said rail, a rocking member carried by said mar- 35 gin stop, movable in opposite directions from a central position, having two con- tact surfaces engaged successively by the stop block during the traverse of the platen in one direction to move the rocking mem- ber first in one direction and then in the other direction, and means under the control of said rocking member.

Signed at New York city, in the county of New York and State of New York, this 21 day of March 1918.

LEWIS C. MYERS.
